UNITED STATES PATENT OFFICE.

EDWARD B. CRAFT, OF HACKENSACK, NEW JERSEY, AND GREGORY BROWN, OF BROOKLYN, NEW YORK, ASSIGNEES TO WESTERN ELECTRIC COMPANY, OF NEW YORK, N. Y., A CORPORATION OF ILLINOIS.

SELECTIVE CALLING APPARATUS.

1,140,120.

Specification of Letters Patent. Patented May 18, 1915.

Application filed June 30, 1910. Serial No. 569,685.

To all whom it may concern:

Be it known that we, EDWARD B. CRAFT and GREGORY BROWN, citizens of the United States, residing, respectively, at Hackensack, in the county of Bergen and State of New Jersey, and at Brooklyn, in the county of Kings and State of New York, have invented a certain new and useful Improvement in Selective Calling Apparatus, of which the following is in full, clear, concise, and exact description.

This invention relates to selective calling apparatus for telephone exchange systems and more particularly to a selector device designed for use on a party line and adapted, in response to impulses sent out from a calling station, to complete a signaling circuit over which the party at the way station receives certain notifications, such as signals to answer, time signals, etc. The invention is directed more particularly to a selector having two magnets, one being a slow-acting one controlling a pawl adapted to engage a ratchet wheel to hold it against rotation in one direction, the other being a quick-acting one and adapted, in response to impulses sent over the line, to step said ratchet wheel around to a definite position determined by apparatus at the calling station. In the class of telephone work to which this selector is particularly adapted, there will be a number of stations on a single line, each station provided with a selector responsive to impulses sent out from a calling station, the several selectors being adapted to close a signaling contact in response to a different number of impulses from the sending station; that is to say, while all of the selectors respond to the impulses sent out over the line when one station is being called, the number of impulses which will close the circuit for signaling the party at any one station on the line will not complete the signaling circuit at any other station on the line. It is frequently desirable, however, in this class of work to send a certain class of signals to all stations simultaneously, and one of the objects of this invention is to provide means for closing a second or auxiliary circuit for the receiving of time or like signals at the way stations. Preferably this circuit is completed through a contact on the selector frame which is engaged by the contact carried by the ratchet wheel—these

contacts in the case of each selector being closed by a different number of impulses than are required to close the calling signal contacts, but closed on all selectors by the same number of impulses.

Another feature of this invention includes a novel arrangement for obtaining an accurate adjustment of the operating parts of the selector.

Other features of our invention are the details of the frame and arrangement of the parts thereon, whereby the apparatus may be assembled into a compact and convenient unit with all of the parts easily accessible and well protected.

In the drawings illustrating this invention—Figure 1 is a view in side elevation of the selector with parts broken away; Fig. 2 is a view in front elevation with parts broken away; Fig. 3 is a vertical sectional view taken upon line 3—3 of Fig. 2; Fig. 4 is a horizontal sectional view taken upon line 4—4 of Fig. 2; Fig. 5 is a bottom view of the selector.

In the drawings, 1 designates a base member upon which is mounted an inverted U-shaped frame preferably formed of sheet metal having side members 2, 2, a top member 3 and supporting lugs 4, 4. Mounted within said U-shaped frame are two electromagnets 5 and 6, each comprising two coils, the coils of each magnet being secured together at their upper ends by a yoke 7 of magnetic material secured to the cores of the coils. The magnets are mounted in the frame by suspending them from the top member 3 of the U-shaped frame, each of said magnets being secured by means of two machine screws 9, 9 passing through a raised portion 10 on said frame and engaging screw-threaded apertures in the yoke 7. A slotted set screw 12 passing through said raised portion 10 bears upon the yoke 7 midway between the ends thereof. The use of the holding screws 9, 9 engaging the yoke 7 permits of easy adjustment of the magnets for increasing or decreasing the air gap and the set screw 12 will hold them firmly in their adjusted position. The raised portion 10 upon the top plate of the frame is for strengthening said top plate at the points where the screws are supported. Pivotedly supported near the lower end of the U-shaped frame are armatures 14 and 15, the

armature 14 being responsive to the magnet 5 and the armature 15 being responsive to the magnet 6. Cross bars 18 and 19 secured to the lower portion of the U frame on either side thereof are each provided with an upwardly and inwardly extending member 20.

A horizontally arranged set screw 21 inserted through the vertical portion of the member 20 is provided with a conical end which is adapted to engage a beveled portion 22 upon the lower face of the adjacent armature while a second set screw 23 inserted through the inturned portion of said member 20 is adapted to engage the upper face of said armature. With this arrangement both the extent and the position of the angle through which the armature moves can be governed to a certain extent, it being evident that as the set screw 21 is moved inwardly or outwardly, the position with respect to a horizontal plane which the armature will assume when in its lower position may be varied within certain limits; likewise by varying the position of the set screw 23 the extent of the movement of said armature may be varied. This feature permits of a more accurate adjustment of the operating parts of the selector as will hereinafter appear.

As hereinbefore mentioned one of the magnets is a slow-acting one adapted to hold a ratchet wheel against rotation in one direction—the other being arranged to step said ratchet wheel around to a predetermined position. As shown, the armatures 14 and 15 are provided with arms 25 and 26, respectively, which are brought out through openings in the frame and extended vertically upward. Attached to the upwardly extending arm 25 is an arm 27 carrying at its upper end a pivotally mounted pawl 28 adapted in the movement of said armature to engage the teeth of a ratchet wheel 29 supported upon the frame in the manner hereinafter described. A spring 31 secured at one end to said pawl and at its other end to the arm 27 tends to force said pawl into engagement with the ratchet wheel 29. A laterally projecting finger 32 on said pawl is adapted to be engaged by an arm 35 controlled by the armature 15 to force said pawl 28 out of engagement with the teeth of said ratchet wheel. Mounted upon the arm 26 of the armature 15 is a metal stamping 33 carrying arms 34, 35 and 36, the arm 35 being for the purpose of pressing the pawl 28 out of engagement with the ratchet wheel 29 as hereinbefore described, the arm 34 being for the purpose of disengaging a holding pawl 40 from the ratchet wheel and the arm 36 being for the attachment of a spring 41 which is adapted, when the magnet 6 is deenergized, to return the armature 15 to its normal position. As shown in Fig.

2 the holding pawl 40 is in the form of a bell crank lever—one arm being adapted to engage the teeth of the ratchet wheel 29, the other arm thereof being adapted for engagement by the upper end of the arm 34. 70

Secured to the frame of the selector on the side member thereof carrying the ratchet wheel 29 are tension members 45 and 46, the tension member 45 being located to the left of the ratchet wheel and having one arm to the lower end of which is attached one end of a spring 47, the other end of which spring is attached to the arm 27, said spring being adapted to act through said arm to return the armature 14 to its normal position 80 when the magnet 5 is deenergized. The member 46 is provided with two arms to which are attached springs 41 and 48, the spring 41 being for the purpose of returning the armature 15 to normal position and the spring 48 being secured at its other end to the pawl 40 for the purpose of drawing it into engagement with the ratchet wheel 29 when the magnet 6 is energized. The tension of the springs 41, 47 and 48 is adjusted by bending the respective arms to which their outer ends are attached. 85

As shown in the drawings, the ratchet wheel 29 is mounted in an auxiliary frame 50 removably secured to the main frame of the selector, said ratchet wheel being provided with a spindle 51 having conical ends engaged by set screws 52 and 53 extending through the walls of said auxiliary frame 50. A helical spring 55 surrounds the spindle 51 and is adapted to return said ratchet wheel to its normal position when both magnets are released. 90

Referring now to the arrangement of contacts whereby the signaling circuits hereinbefore referred to are completed, same is as follows: Carried upon the ratchet wheel 29 is an arm 60 having an offset portion 61 at its outer end upon which is mounted an outwardly facing contact member 62. Said contact member 62 is adapted in the rotation of said ratchet wheel to engage a contact 63 carried by the upper end of a spring 64 mounted on one side of said ratchet wheel. The spring 64 is mounted upon a 110 projecting support 67 formed integrally with the main frame. Said spring 64 is flexible and is provided at its upper end with a laterally projecting finger 65 which engages an insulating block upon the outer 115 face of the arm 27. The flexibility of the spring 64 and its connection with the arm 27 causes it to partake of the movement of said arm 27 as it operates to step around the ratchet wheel 29, thus bringing it into 120 contact with the contact member 62 on the forward movement of the arm 27 or during the time that the stepping magnet 5 is energized. The arm and spring are so adjusted, however, that these contact members 125

62 and 63 will be engaged only during one step of the stepping magnet. When in its normal position the contact arm 60 rests against an insulated stop 70, carried by a depending stop arm 71 which is itself insulated from the auxiliary frame 50. Mounted upon the opposite side of the arm 71, from that against which the arm 60 rests when in normal position, is a contact 72 which is in position to be engaged by contact point 62 when the ratchet wheel is rotated through substantially a complete revolution. A terminal strip 75 connected with the depending arm 71 is brought out through an insulating bushing 76 in the frame 50 for connection with a conductor. A terminal strip 80 connected with the spring 64 extends downwardly through a hole in the base 1 for connection with a conductor. Another connection is completed through the selector frame. The stop arm 71 is made adjustable so that by swinging it to the right or left, the number of steps necessary to close the contacts 62 and 63 may be increased or decreased.

A projecting ear 85 formed integrally with the auxiliary frame 50 forms a support for a stop screw 86 which is adapted to limit the forward movement of the pawl 28. Inasmuch as the arm 27 carrying the pawl 28 is rigidly secured to the armature 14 these elements move together and the positions of the arm with respect to the ratchet wheel in which the movements of said arm will take place may be varied by varying the extent and position of the angle through which said armature moves. By so varying this movement the points on the periphery of the ratchet wheel 29 at which the pawl 28 will engage therewith may be varied, thus permitting of a finer and more accurate adjustment of the operating parts.

The operation of a selector made as hereinbefore described is as follows: At the first impulse of current which comes over the line, both magnets will be operated, but the adjustment of the parts is such that this first impulse will not step the ratchet wheel forward but will bring the holding pawl into engagement with said ratchet wheel. The succeeding impulses, however, will step the ratchet wheel around and the holding pawl being controlled by the slow acting magnet will be held in engagement with the ratchet wheel during the time that the impulses are operating the stepping magnet. When the contact 62 of the selector at the called station has been brought into register with its contact 63, the movement of the selector will be stopped for an interval with the contacts 62, 63, completing a circuit through a signaling device. This circuit will remain closed a certain interval under control of the sending apparatus when the current will be cut off from the line, de-

energizing the magnets and permitting the ratchet wheel to return to its normal position. In case it is desired to signal all of the stations simultaneously, a sufficient number of impulses will be sent out to step all of the selectors around until the contact points 62, 72 are brought into engagement. The same number of impulses over the line will step all of the selectors around until the contacts 62, 72 are closed.

The use of the U-shaped frame inclosing the electromagnets and providing a mounting for the operating parts of the selector makes a compact piece of apparatus with all of the parts easily accessible. The means of adjusting the tension of the springs by the tension members 45 and 46, thus doing away with the screws or other like adjusting means susceptible to jar and vibration, is also of considerable advantage. The selector when in use will be mounted upon a suitable base and the parts protected either by a porcelain or glass hood.

We claim:

1. In a selector device the combination with a frame embracing top and side members, of magnet coils suspended from said top member, armatures pivotally supported between said side members below said coils, arms formed integrally with said armatures and extending outwardly and upwardly along the outer face of one of the side members, an auxiliary frame removably mounted upon the side member of the first mentioned frame adjacent to said arms, a ratchet wheel pivotally supported upon said auxiliary frame, spring pressed pawls operated by said arms for turning said ratchet wheel in one direction, and a helical spring operating to turn said ratchet wheel in the opposite direction.

2. In a selector device, the combination with a frame, of a ratchet wheel mounted thereon, an oscillating operating arm adapted to be moved to step said ratchet wheel around, an arm carried by said ratchet wheel, said arm having an offset portion at its outer end, a contact carried by said offset end, a flexible spring mounted on said frame, a laterally projecting finger on said spring, an insulating knob on the back of said operating arm against which said finger normally bears, and a contact on said flexible spring adapted to be brought into engagement with the contact carried on the ratchet wheel arm during one step only of said wheel.

3. In a selector device, the combination with electromagnets and a frame therefor, of an auxiliary frame mounted upon said magnet frame, a ratchet wheel mounted in said auxiliary frame and adapted to be stepped around under action of said electromagnets, a contact arm movable with said ratchet wheel, a spring contact mounted upon the magnet frame near the periphery

4

of said ratchet wheel and with which said movable contact arm registers when said ratchet wheel has been moved through a definite angle, a stop arm mounted on said auxiliary frame and insulated therefrom, an insulated stop on said arm against which the movable contact arm rests when in normal position, and a contact on said stop arm adapted to be engaged by the contact 10 on the arm carried by the ratchet wheel when said ratchet wheel has been rotated the full extent of its movement.

4. In a selector device the combination with an inverted U-shaped frame, of an 15 electromagnet suspended therein, an armature responsive to said electromagnet pivotally supported in said frame below said electromagnet, a ratchet wheel removably supported upon said frame, operative connections 20 between said armature and said ratchet wheel, and means for varying the extent and position of the angle of movement of said armature, said means comprising set screws carried upon said frame and 25 engaging the upper and lower face of said armature.

5. In a selector device the combination with an inverted U-shaped frame, of an electromagnet suspended therein, an armature responsive to said electromagnet pivotally supported in said frame below said magnet, 30 said armature being provided with a beveled portion, a ratchet wheel mounted upon one side of said frame, operative connections between said ratchet wheel and said armature, a cross bar mounted upon said frame adjacent to said armature, an upwardly and inwardly extending member carried by said cross bar, a conical ended set screw extending through the upwardly extending portions of said member and engaging the beveled portion of said armature, and a set screw extending through said inturned portion of said member in position to engage 35 the upper face of said armature.

In witness whereof, we hereunto subscribe our names this 29th day of June A. D., 1910.

EDWARD B. CRAFT.
GREGORY BROWN.
